UNITED STATES PATENT OFFICE.

THOMAS M. CAMPBELL, OF NORTH AUGUSTA, SOUTH CAROLINA.

DESIGN FOR THE FRONT OF A GARAGE.

54,061.

Specification for Design.

Patented Nov. 4, 1919.

Application filed June 7, 1919. Serial No. 302,602. Term of patent 3½ years.

To all whom it may concern:

Be it known that I, THOMAS M. CAMPBELL, a citizen of the United States, residing at North Augusta, in the county of Aiken and State of South Carolina, have invented a new, original, and ornamental Design for the Front of a Garage, of which the following is a specification, reference being had to the accompanying drawing, which shows the front of a garage, with miniature model or picture of an automobile proportionate to the size of the garage placed in the top panel of the front of the building, as shown.

The figure is a front view of the front of a garage, showing my new design.

I claim:

The ornamental design for the front of a garage, as shown.

THOMAS M. CAMPBELL.
